UNITED STATES PATENT OFFICE.

MARLON H. WINSLOW, OF TERRE HAUTE, INDIANA.

PLATFORM SCALE.

Application filed March 22, 1920. Serial No. 367,695.

To all whom it may concern:

Be it known that I, MARLON H. WINSLOW, a citizen of the United States, and a resident of Terre Haute, county of Vigo, and State of Indiana, have invented a certain new and useful Platform Scale; and I do hereby declare that the following is a full, clear, and exact description thereof, reference being had to the accompanying drawings, 10 in which like numerals refer to like parts.

This invention relates to platform scales suitable for railroad cars and vehicles of lighter construction, wherein the scale is constructed of but few levers and these of improved form.

The chief object of this invention is to reduce the cost of constructing and maintaining the knife edges of the various levers by shaping the lever in an improved 20 manner to permit machining the knife edges thereof while the same are embedded in the lever.

One feature of the invention consists in embedding the knife edges in the lever casting and having the individual edges extending transversely across the lever to permit a planer, shaper, or similar machine tool to pass along the entire length of the individual edge which permits the latter 30 to be machined to the same and desired bevel surface on each side of the knife edge with substantial accuracy and increased economy.

A further feature of the invention consists in embedding the knife edges in the lever which prevents any warping of the knife edges occasioned by the tempering thereof, since the edge will be forced into proper alignment when the same is driven 40 into the cast recess formed in the lever.

A further feature of the invention consists in positioning the knife edges line in a plane which substantially coincides with the horizontal plane through the center of gravity of the scale lever. This construction secures more sensitive action of the scale.

In said scale also, all of the levers are of the second class and all of them move downwardly under the influence of the load and the levers receiving the load directly from the platform and the two longitudinal levers which transmit the load to the central cross lever all transmit their power by a downward push instead of a downward pull.

These and the foregoing features of such scale greatly simplify the construction of the scale, in fact, reducing the number of parts in a railway platform scale from about 300 to about 40.

The full nature of this invention will be understood from the accompanying drawings and the following description and claims.

In the drawings Fig. 1 is a plan view of a platform scale embodying the features of the invention. Fig. 2 is an enlarged elevational view of one of the main side levers showing in detail one of the features of the invention, and is taken on the line 2—2 of Fig. 1 and in the direction of the arrows. Fig. 3 is a top plan view of the main side lever shown in Fig. 2 and illustrates another feature of the invention.

In the drawings there is shown a platform scale including a suitable pit 10, a cross lever 11 connected at one end to the beam rod, not shown, while the other end is supported upon a cross lever stand 12 positioned centrally beneath the scale platform 13. In spaced relation with each other and in each corner of the pit is a main side lever stand 14 which supports one end of the main side lever 15, the other end being supported by the end extension lever 16. The end extension lever 16 is supported at one end upon the end extension lever stud 17 and the other end is supported by the cross lever 11, as shown in Fig. 1. As illustrated the scale consists of four main side levers suitably supporting the usual scale platform, two end extension levers supporting the adjacent ends of two of the main side levers, the adjacent ends of said extension levers being suitably supported by the cross lever, the latter being connected to the beam rod, not shown.

The end extension levers 16 and the main side levers are of substantially the same design. Figs. 2 and 3 illustrate the improved lever construction which incorporates the chief features of the invention. Since all the levers are substantially similar, a description of one of the main side levers will be given. In Figs. 2 and 3 the main side lever 15 is shown provided with a vertical longitudinal rib portion 20 extending substantially the entire length thereof. Extending transversely of said ribbing are the transverse bracket portions 21, the same

being positioned upon each side of the lever and upon each side of an opening 22 formed in said ribbing. In one end of the lever 15, in a suitable cast recess or slot 23, is embedded the knife edge 24. Upon the opposite end of the lever 15 is a similar recess or slot 25 in which a similar knife edge 26 is secured. The recesses or slots 23 and 25 extend transversely of the ribbing 23 and are 10 adapted to receive the tempered knife edges 24 and 26 respectively. As shown clearly in Fig. 2 said knife edges are exposed upon the lever such that both beveled faces of each knife edge may be machined for sharpening 15 and resharpening without removing the knife edges from the lever. In this manner the required bevel can be maintained without disturbing the multiple of said lever. Positioned in the slot 22 and extending trans- 20 versely of said lever is a load supporting knife edge 27, the same similarly embedded in a bearing block 28. The bearing block 28 is adjustably positioned between the brackets 21 by means of the jam bolts 29, 25 as shown. This feature of the construction is shown in Patent No. 803,456 dated October 31, 1905. As described in said patent the knife edge 27 may be adjusted to the exact 30 multiple desired by turning the respective bolts 29 in the proper direction and a suitable amount.

As illustrated in Fig. 3 the knife edges 24, 27 and 26 extend substantially across the lever 15 and the entire length thereof. As 35 illustrated in Fig. 2 the knife edges 24 and 26 are exposedly positioned upon the lever 15 which permits the knife edges to be machined, as described. Preferably the knife edges 23 and 26 are cast with the lever 15 and the knife edge 27 is cast integral with the bearing block 28. Although the same is 40 not illustrated it will be understood that the end extension levers are constructed similarly to the main side levers described.

In Fig. 2 the horizontal line $x-x$ representing the plane in which the knife edges lie, corresponds to the horizontal plane including the center of gravity of the lever. With this construction the scale responds 45 more readily and is more sensitive than if otherwise constructed.

All of the levers in said scale are levers of the second class only and said six levers 15 and 16, which receive the load from the platform and transmit it to the central cross frame 11, have downward movement under the influence of the load and transmit their power by pressing downward on the lever to which they transmit the power instead of 50 being suspended or pulling downward.

This enables a scale of this kind to be made with only 7 levers and with only 40 pieces under the platform. This system of leverage makes it unnecessary to have a single forging or link or clevis under the plat- 55

form, as well as renders the bearings and knife edges and associated parts accessible for inspection and truing up and for the knife edges to be in the same horizontal plane and the center line of gravity in each 70 lever.

The invention claimed is:

1. A platform scale including a platform, a pair of transverse levers under each end of the platform, a cross lever for actuating a weight-indicating mechanism, a longitudinal lever for transmitting the effect of the load from the transverse levers at each end to said indicating actuating lever, and connections between said levers, all of said levers being of the second class of leverage. 75

2. A platform scale including a platform, a pair of transverse levers under each end of the platform, a cross lever for actuating a weight-indicating mechanism, a longitudinal lever for transmitting the effect of a load from the transverse levers at each end to said indicating actuating lever, all of said levers being of the second class of leverage, 80 and connections between said levers permitting the levers to rest upon and push each other downward under the influence of a load, substantially as set forth. 90

3. A platform scale including a platform, a pair of transverse levers under each end of the platform, a cross lever for actuating a weight-indicating mechanism, a longitudinal lever for transmitting the effect of a load from the transverse levers at each end to said indicating actuating lever, all of said levers being of the second class of leverage, 95 and knife edge bearings between and mounted in the adjacent parts of said levers and arranged so that the actuated end of each lever rests upon and forces downward the actuated lever under the influence of the load. 100

4. A platform scale including a platform, a pair of transverse levers under each end of the platform, a cross lever for actuating a weight-indicating mechanism, a longitudinal lever for transmitting the effect of a load from the transverse levers of each end to said indicating actuating lever, all of said 110 levers being of the second class of leverage, and knife edge bearings operatively connecting said levers and for fulcruming each of said levers, all of said bearings being exposed to render them accessible for inspection and machining. 115

5. A platform scale including a platform, a pair of transverse levers under each end of the platform, a centrally located cross lever for actuating a weight indicating mechanism, a centrally-located longitudinal lever for transmitting the effect of the load from the transverse levers of each end to the central weight indicator actuating lever, said longitudinal levers being in alignment with each other, all of said levers being of the second class of leverage, and each lever overlap- 120 125 130

ping the portion of the lever actuated by it, and knife edge bearings located between the overlapping portion of said levers.

6. A platform scale including at least seven levers and having all of its knife edges lying in the same plane when in a normal or balanced condition, said levers having their

centers of gravity in a horizontal plane, said knife edge plane and said center of gravity plane substantially coinciding, whereby sensitive action of the platform scale is secured. 10

In witness whereof, I have hereunto affixed my signature.

MARLON H. WINSLOW.
